UNITED STATES PATENT OFFICE.

CHARLES P. MORTON, OF CINCINNATI, OHIO.

LAST-LATHE.

1,199,407.

Specification of Letters Patent. Patented Sept. 26, 1916.

Application filed November 26, 1915. Serial No. 63,383.

To all whom it may concern:

Be it known that I, CHARLES P. MORTON, a citizen of the United States of America, and resident of Cincinnati, county of Hamilton, State of Ohio, have invented certain new and useful Improvements in Last-Lathes, of which the following is a specification.

This invention relates to last lathes and particularly to the means for mounting and driving the cutter head of the blade.

An object of my invention is to produce a means for mounting and driving the cutter head of the lathe in such a manner that the large drum ordinarily employed in last lathes, for driving the cutter head, is eliminated.

Another object of my invention is to provide a means for driving the cutter head, to take the place of the usual drum, and which may be mounted in the usual bearings of the shaft of the cutter head.

A further object of my invention is to produce a means for mounting and driving the cutter head in such a manner that the speed of rotation of the cutter head may be controlled independently of the speed of the lathe.

A further object is to produce a means for mounting and driving a cutter head in such a manner that the vibration created by the drum ordinarily employed for driving the cutter head, is eliminated.

These and other objects are attained in the cutter head mounting and driving means described in the following specification and illustrated in the accompanying drawings in which the figure is a perspective view of a cutter head driving mechanism embodying my invention, of the carriage upon which the cutter head is mounted, and a fragment of the ways of the lathe bed upon which the carriage is reciprocally mounted.

In the usual last lathe construction a carriage 1 is provided for carrying the cutter head 2 in a suitable manner and in a position to engage the block from which the last is being turned. This carriage is reciprocally mounted on ways 3-3 formed on the supporting frame members 4-4 of the lathe bed. In the usual last lathe construction the cutter head is driven from an elongated drum which rotates beneath the bed of the lathe and from which passes a belt which reciprocates on its ways 3-3. In my im-

proved construction I eliminate the drum and in place of the drum I provide a motor driven pulley and a bracket 5 therefor which is supported on the carriage. This bracket 69 has bosses 6 and 7 in which short lengths of shaft 8 and 9 are mounted, which have bearing in the usual bearing blocks 10 and 11 formed on the reciprocating carriage 1. The boss 7 is located at a distance from the body 65 of the bracket 5 at the end of an arm 12 extending from the bracket, so that the bracket will occupy an angle to the line of the shaft for which the bearings 10 and 11 are provided, as shown in the drawing. At the top 70 of the bracket 5 and in alinement with one another, bearings 13 and 14 are provided, these bearings being adapted to receive the cutter shaft 15. With such a construction the cutter shaft is held at an angle to the line 75 of the ways of the bed so that the cutter head is presented to the work being turned, at an angle thereto in the position shown in the drawing.

The bracket 5 is provided with a depending extension 16 provided with a clamp 17 adapted to receive the stem 18 of a plate 19 upon which a driving motor 20 is mounted. The stem 18 is held within the clamp by a collar 21 which is screwed thereon and which is 85 provided with openings 22 for receiving a spanner wrench so as to raise or lower the position of the plate with relation to the clamp 17. Bolts 23 are provided on the clamp for securing the plate 19 in its adjusted positions either raised or lowered or when turned to various angles. Upon the underside of the plate 19 the driving motor 20 is mounted, the motor being secured thereto by any suitable means such as nuts 95 and bolts 24. This motor is provided with a driving pulley 25 over which passes a driving belt 26 which in turn drives the pulley 27 mounted on the cutter shaft 15. By this means the cutter may be driven at varying or uniform speeds by controlling the motor 20, the operation thereof being absolutely independent of the operation of the lathe, and by means of the bolts 23 and collar 21 the motor pulley 25 may be adjusted to adjust 100 the tension or position the belt 26. In order to steady the bracket 5 and to prevent its swinging after it has been placed in the bearings 10 and 11 of the carriage 1, I have provided clamping lugs 28 and 29 extending 105 from the side of the bracket and engaging pins 30 and 31 bolted to the carriage 1. By

tightening the bolts 32 and 33 in the lugs 28 and 29 the bracket is mounted rigidly on the carriage.

By means of my improved construction I 5 am enabled to obtain a very high speed of the cutter head because of its driving mechanism being completely isolated from the other driving mechanism of the lathe. This cannot be obtained in the present last lathe 10 construction.

Another advantage attained in my improved construction is the elimination of excessive wear on the belts employed for driving the cutter head, due to strains occasioned by the passage thereof over idlers 15 which reversely bend it.

A further advantage obtained by my improved construction is the elimination of vibrations produced by the usual cutter head 20 driving drum, especially the elimination of the vibration produced by the drum in the swinging frame which carries the master last and the block from which the stock last is being made. In addition to this the construction embodying my invention may be 25 mounted in the usual bearings of the carriage and thus obviate the necessity of changing the construction of the lathe. Furthermore, the speed at which the cutter 30 shaft may be run enables me to use a cutter head of small diameter, which has the advantage of being able to turn the last to any desired depth which may be required on the hollow side thereof.

35 Having thus described my invention, what I claim is:

1. A means for mounting and driving cutter heads of last lathes of the character described, comprising a carriage mounted on 40 the lathe bed and having a depending bracket extending therefrom, bearings formed on the carriage above the bracket, a cutter head shaft supported by the bearings, a motor mounted in the lower end 45 of the bracket, and means operatively connecting the motor and the shaft.

2. In a mounting and driving means for cutter heads of last lathes of the character described, the combination of a carriage 50 reciprocally mounted on the lathe bed, a depending bracket carried by the carriage, a motor adjustably mounted at the lower end of the bracket, a cutter head rotatively mounted on the bracket, and means operatively connecting the motor and the cutter head.

3. In combination in a mounting and

driving means for cutter heads of last lathes of the character described, a carriage mounted on the lathe bed, a depending bracket 60 mounted on the carriage, a motor adjustably mounted at the lower end of the bracket, bearings at the upper end of the bracket, adapted to rotatively mount the cutter head at an angle to the line of travel of the carriage, and means operatively connecting the motor and the cutter head.

4. A means for mounting and driving last lathe cutter heads comprising a carriage mounted on the lathe bed, bearings 70 formed on the carriage, a bracket hung in the bearings, a cutter head shaft journaled in the upper end of the bracket, a motor mounted in the lower end of the bracket, a pulley mounted on the driving shaft of 75 the motor, and a belt operatively connecting the pulley and the cutter head shaft.

5. In a mounting and driving means for last lathe cutter heads a combination of a carriage mounted on the lathe bed, bearings 80 formed on the carriage, a bracket hung in the bearings and having a clamp at its lower end, a cutter head shaft journaled in the upper end of the bracket, a motor mounted in the clamp at the lower end of the bracket, 85 a pulley mounted on the driving shaft of the motor, and a belt operatively connecting the pulley and the cutter head shaft, said clamp being adapted to afford upward, downward or transverse adjustment of the 90 motor to adjust the tension or position of the belt.

6. In combination in a mounting and driving means for cutter heads of last lathes of the character described, a carriage mounted 95 on the lathe bed and having a depending bracket extending therefrom, bearings formed on the carriage above the bracket, a cutter head shaft supported from the bearings, a clamp located at the lower end of 100 the bracket, a motor mounted in the clamp, and means operatively connecting the motor and the cutter head shaft, the clamp being adapted to render the motor adjustable upwardly, downwardly or transversely to 105 adjust the connecting means.

In testimony whereof, I have hereunto subscribed my name this 20th day of November, 1915.

CHARLES P. MORTON.
